UNITED STATES PATENT OFFICE.

WILLIAM C. GIGGAL, OF DENVER, COLORADO.

FORM CLAMP.

Application filed August 4, 1924. Serial No. 729,957.

This invention relates to clamps for use in assembling the component parts of a mold or form of the type employed in constructing columns and other similar structures of concrete or other plastic material.

It is an object of the invention to provide a clamp of this character which will insure a true angular relation of the assembled parts of the concrete mold to which it is applied, in a simple manner and without intricate adjustment or measurement and another object is to form a clamp of the above stated characteristics of two simple members cooperatively connected and relatively adjustable for the application of the clamp to forms of different cross-sectional areas.

A further object of the invention is to provide in association with the clamp members, a lever of novel form to forcibly adjust the members to their proper relative position around the mold and still other objects reside in details of construction hereinafter described and shown in the accompanying drawings in the several views of which like parts have been similarly designated.

In the drawings,

Figure 1 represents a perspective view of the clamp with the parts thereof relatively disposed and connected for application to a concrete form;

Figure 2, a fragmentary elevation of a concrete form, showing two of my improved clamps in place thereon;

Figure 3, a section along the line 3—3, Figure 2, drawn to an enlarged scale;

Figure 4, an enlarged fragmentary section taken on the line 4—4, Figure 1; and

Figure 5, an enlarged fragmentary section along the line 5—5, Figure 1.

Referring more in detail to the drawings, 5 designates a mold for forming columns of rectangular section, comprising four upright members 6 preferably composed of boards.

The members are held together in true rectangular formation by a plurality of my improved clamps applied at different elevations thereof.

Each clamp consists of two co-ordinating angular sections 7 identical in construction and composed of a plurality of members rigidly connected at an angle to each other which corresponds with an angle of the concrete form to which the clamp is applied.

In the form of my invention shown in the drawings, the members of the clamp-sections are relatively disposed to form a square

mold but it is to be understood that by a different arrangement of the members, the clamps may likewise be employed in the construction of molds which are of different polygonal shape in cross-section.

Each section of the clamp consists of a double strap-member 8 and a single strap member 9 rigidly fastened together at right angles to each other by rivets 10 applied at the point of their intersection and by cross-braces 12 fastened to and between the extremities of extensions 8^a and 9^a of the members by rivets 13.

The members are provided at their free ends with longitudinally and equidistantly spaced apertures 8^c and 9^c for the reception of headed pins by means of which the sections are fastened together.

For the application of the clamp to a form of the construction illustrated in Figures 2 and 3, the two sections are pivotally fastened together by a pin 14 inserted in aligned corresponding apertures of two of its members which cross each other at a distance from the opposite members of the sections, equal to the external width of the form.

The clamp is then placed around the form and a lever is fulcrumed by means of a pin 16 in opposite apertures of the free double member 8 of one of the sections to engage with the outer edge of the corresponding single member 9 of the other section.

The lever consists of a bar 15 having at one end a notch 15^a to straddle the edge-portion of the strap-member 9 of the clamp as best shown in Figure 5, and at a comparatively short distance from said notch it has an aperture 15^c to receive the pin 16. The lever 15 which is provided at its engaging end with spaced sides or flanges and a connecting web or portion, is provided in the web with the recess or notch 15^a, which extends longitudinally of the lever. The side walls of the notch or recess 15^a preferably converge inwardly as shown in Fig. 5.

It will be evident that by pivotal movement of the lever applied to the pivotally connected clamp-sections as hereinabove explained, the free ends of the sections are forcibly drawn toward the sides of the mold until their apertures corresponding to those of the ends connected by the pin 14, are brought into register when by the insertion of a pin 17 through said apertures, the members are fastened in their adjusted relation.

The members of the sections thus connect-

ed are in true rectangular formation and the clamp will securely hold the parts of the form in their proper relative position and against displacement or deformation by 5 the expansive pressure of the plastic material with which the mold is filled.

The lever after having been removed from one clamp may be employed for the application of another clamp and any number of the 10 clamps may thus be tightened around the form as is required to insure its strength and rigidity.

Having thus described my invention, what I claim and desire to secure by Letters 15 Patent is:

A clamp comprising a rectangular frame composed of bars crossed at the corners of the frame and extended beyond the same, the bars at two opposite sides of the frame being

arranged in pairs and the bars at the other 20 sides of the frame being single bars, means for rigidly connecting the extended ends at two diagonally opposite corners of the frame, the extended ends of the bars at the other two corners of the frame being provided at intervals with perforations for the reception of pins, and a lever for adjusting the bars, said lever being pivoted near one end between the pair of bars at one corner of the frame and provided at the pivoted 30 end with a notch extending longitudinally of the lever and permitting the lever to straddle the adjacent single bar for fulcruming the lever against the outer edge thereof.

In testimony whereof I have affixed my signature.

WILLIAM C. GIGGAL.
